UNITED STATES PATENT OFFICE

DANIEL PENNER AND ISRAEL FEINTUCH, OF KINGSTON, NEW YORK

MATTRESS

Application filed October 22, 1930. Serial No. 490,348.

This invention relates to improvements in mattresses, cushions, pillows and the like, as used by persons while at rest in a reclining or sitting position, and although the description and showing reveal the invention as being in the form of a bed mattress, it will be understood that sizes and proportions may be varied at will.

Ordinarily mattresses may be turned to present either end at the head and also either side uppermost; occasionally they are made in such manner that one side has a different feel or texture, relatively soft or hard, and some have fixedly incorporated in them metallic springs as a unit.

In the present development it is an object to provide a mattress, using the term generically, so constructed as to permit reversing of its sides and furthermore, which can be inverted or in other words turned inside out, thereby presenting double the number of surfaces available in an ordinary mattress, together with corresponding changes in kind and color of facing material.

A further feature is in the provision of a mattress made in two substantially equal body sections hingedly engaged at one of their edges and provided with means for detachably connecting their free edges, along their entire lengths, when the sections are in operative position with either side exposed.

Another aim is to provide a mattress having equal body sections, invertibly connected, with partitions, spaced parallel between their outer surfaces, providing chambers each to be filled with different material, as curled hair, feathers, lamb's wool, cotton batts, kapok, silk floss, etc., etc., whereby a diversified yielding effect may be obtained by turning the mattress to present the preferred side uppermost.

A still further feature is to produce a mattress formed of connected sections which may be spaced, and a unitary spring element removably engageable in the space, intermediate the body sections.

These and other advantageous objects are attained by the novel and practical construction, combination and arrangement of parts hereinafter described and shown in the ac-

companying drawings, constituting an important component of this disclosure, and in which:—

Figure 1 is a perspective view of a mattress embodying the features of the invention. 55

Figure 2 is a transverse sectional view taken on line 2—2 of Figure 1, showing a preferred form.

Figure 3 is a fractional sectional view of the mattress drawn to an enlarged scale. 60

Figure 4 is another sectional view showing a modified form of construction mainly consisting of the interposition of a spring body between the mattress sections.

Figure 5 is a fragmentary transverse sectional view showing the rolled edges of the mattress more closely drawn together as when under compression.

The mattress illustrated in Figure 1 is of the usual elongated rectangular type in its general appearance and will be seen to consist of two body sections 10 and 11 substantially equal in their general dimensions.

Each section is enclosed in a casing made of any preferred woven textile fabric, as damask ticking, the opposite sides of each section as A and B varying as may be preferred in kind and color of fabric, so that when the sections are inverted as to present a different appearance, or if preferred, each side may differ from any of the others. 75

Rolled edges 12 and 13 are formed circumjacent the outer and inner marginal corners respectively of the sections, and a series of tufts 14 are stitched through each section. 85

Sewn to the edge portions of each mattress section, closely interadjacent the rolled edges 12 is a strip of strong fabric 15 and a similar strip 16 is attached in like manner adjacent the proximate rolled edges 13, the arrangement being such that either of the strips may be positioned outwardly in accordance with the position of the sections 10—11. 90

As seen in Figures 2 and 3 the tickings A—A are outermost and so is the strip 15; but upon inverting the sections to present the tickings B—B outwardly, by folding the sections reversely from that shown, the strip 16 would be on the outside, as these two strips 100

together constitute what in effect is a hinge along one side of the mattress.

On the side opposite the hinge, and also at both ends, the strips 15-16 are both cut 5 longitudinally to present members 15', 16', each pair of strip edges being provided with hookless fastener elements 17-18 served by a runner 19 arranged for manual operation from each side, as obviously it will be reversed when the mattress body portions are turned inside out.

The space between the strips 15-16 is preferably padded as at 20 to constitute a cushion border on each of the four sides giving an 15 attractive box-like appearance and increasing the comfort of its use.

The preferred form, seen in Figure 2, shows flexible sheet partitions 21-22 extended midway the coverings A-B and secured by sewing to each of the four edges 20 of both sections respectively.

These partitions form two individual chambers in each of the mattress body sections and may be filled with any preferred 25 material, as the curled hair in chamber 23, kapok or silk floss in chamber 24, feathers or lamb's wool in chamber 25 and cotton batts in chamber 26, these being used selectively 30 to suit cold or hot seasons, and conditions and comfort of the individual using the mattress, any preferred substance being brought 95 into operative position by proper manipulation.

If it be desired a spring action may be obtained by inserting between the two main 35 body sections 10-11, a removable section composed of a series of conical or spirally wound springs 28 suitably secured at their opposite ends by cross connections 29 to constitute a unit, which may be covered with 40 burlap or other strong fabric.

This arrangement is possible due to the flexibility of the padded borders 20, and by reason of the ready reversibility of the main 45 sections any of the four surfaces may be placed outermost.

It is further noted that insecticides, germicides, disinfectants, perfumery, and the like, may be placed between the sections in the 50 form of crystals, spraying or any convenient form.

Although the improvements have been described with considerable detail and with respect to certain particular forms of the invention, it is not desired to be limited to such details since many changes and modifications 55 may well be made without departing from the spirit and scope of the invention in its broadest aspect.

Having thus described the invention, what 60 is claimed as new and desired to secure by Letters Patent, is:—

A bed mattress comprising two substantially equal stuffed rectangular portions, each 65 having padded rolls extending circumambi-

ently along their upper and lower peripheral edges, a pair of fabric hinge strips of uniform width attached at the junction of each roll and its corresponding peripheral edge to extend from one portion to the other along one of their side edges, separate fabric strips attached at one of their edges in paired relation at the junction of each roll and its corresponding peripheral edge to extend around the opposite side edge and both end edges, 70 padding interposed between the strips on said sides and edges, and slideable means for connecting and disconnecting the unsecured edges of said strips.

In testimony whereof we affix our signatures.

DANIEL PENNER.
ISRAEL FEINTUCH.
